UNITED STATES PATENT OFFICE.

EMIL T. ERICKSON, OF SALT LAKE CITY, UTAH, ASSIGNOR TO RAINBOW PETROLEUM PRODUCTS CO., OF SALT LAKE COUNTY, UTAH, A CORPORATION.

OIL EXTRACTING AND REFINING APPARATUS.

1,281,330.

Specification of Letters Patent. Patented Oct. 15, 1918.

Application filed April 15, 1912. Serial No. 229,869.

To all whom it may concern:

Be it known that I, EMIL T. ERICKSON, a citizen of the United States, residing at Salt Lake City, in the county of Salt Lake and State of Utah, have invented certain new and useful Improvements in Oil Extracting and Refining Apparatus, of which the following is a specification.

My invention relates to oil extracting and refining machinery, and has for its objects to provide an apparatus wherein oil may be extracted from previously mined oil shale and partially refined during the process of extraction by new and novel means which are efficient and economical.

These and other objects which will be apparent I accomplish with the apparatus illustrated in the accompanying drawings in which similar letters and numerals of reference indicate like parts throughout the several figures and as described in the specification forming a part of this application and pointed out in the appended claims.

In the drawings in which I have shown a substantial embodiment of my invention Figure 1 is a view partly in elevation and partly in vertical section of the firing end of my apparatus. Fig. 2 is a view partly in elevation and partly in section of the other end of the same apparatus. Fig. 3 is a longitudinal vertical section on line 3-3 of Fig. 1, with some parts shown in elevation. Fig. 4 is a longitudinal horizontal section on line 4-4 of Fig. 1, with some parts shown in elevation. Fig. 5 is a horizontal section on line 5-5 of Fig. 2 with some parts shown in elevation. Fig. 6 is a vertical section on line 6-6 of Fig. 1 to illustrate the draft conduits.

In a great many places in the United States and particularly in the West there are deposits of shale impregnated with hydrocarbon oils and the present invention is to be used to extract the said oil from the shale after it has been mined, and crushed or ground preparatory to the extraction and in partially refining said oil and separating the light oils such as naphtha from the heavy oils such as the lubricating cuts, and other products, and it is my intention to construct a number of units, each consisting of two adjacent coacting retorts 1 made of boiler plate metal sheets 4 reinforced and supported by brick or masonry walls A, and supported by a concrete base E. Under each

retort 1 is provided a shale pit O which has a door B through which the waste or gangue is removed. Other reinforcements are provided for said walls A by the channel-iron braces 40. F also provide beams 41 and 60 plates 42 on the upper side of the walls A by which the shale pipe 31 is secured to the roof 43 of each retort 1 and the retort and wall fastened together. The walls A and the retort walls are spaced apart as shown 65 at F to form a part of the furnace. The furnace for the initial firing of each unit is constructed between the retorts 1 with its entrance in the rear through the fire box door C and ash pit door D as shown in Fig. 2. The 70 fire is started on the grate bars a and with additional heat supplied through the gas burners 6 zones of combustion as shown at 7 are supplied near the base and around the walls 4 and act on the shale in the retorts 1, 75 and out through the openings 33 and smoke pipe 34. Arches 37 are built across the fire boxes to connect the combustion zones with each other and allow the heat from all of the 80 said burners 6 to act on the retorts 1. As previously stated the retorts are constructed in pairs with their furnace between them and their outer walls spaced apart and from the masonry walls A to allow the heat to act on all sides and end walls thereof. Each 85 retort consists of a narrow rectangular chamber 1 having hinged doors 3 as a bottom closure with braces 3^a to support them. Above said doors 3 are the check grates 5 which regulate and control the shale as it is 90 passed through the said retorts. Coacting gear wheels G are provided on the ends of the grate shafts 50 by which said doors 3 may be simultaneously dumped, and a similar arrangement is provided to operate the 95 check grates 5. The end bearings for the shafts 50 are shown at 20 with the lubricating cups at 19 and stuffing boxes for said shafts at 13. Angle plates 15 are provided as bearing standards for said shafts 50 and 100 these plates with the shield plates 23 and plates 16, 17, 18 and 23^a form an arch and supports for the masonry around the openings through which the grates 5, doors 3 and their connections are placed in position and operated. The pipes 8 are provided adjacent the bottom of the said retorts 1 to introduce a small quantity of steam into the shale under treatment. A plurality of horizontal pipes with openings 51 therein are 105 110

longitudinally placed, one above the other, in the said retorts 1 with closure caps 21 screwed on one end. The opposite ends of the lower three of said pipes shown at 10 5 are connected for discharge through the pipe 29. The ends of the six pipes next above said pipes 10, as shown at 11, are connected for discharge through the pipe 28, and the two pipes nearer the top of said retorts, 10 shown at 12, are connected for discharge through the pipe 30. Stuffing boxes 24 are shown on the said pipes 10, 11 and 12 to seal the opening around said pipes where they pass through the end wall 22 of said retorts. A pipe line 35 is provided to introduce air for the gas burners 6 and another pipe line 36 is also provided to introduce the gas used in the furnaces.

The operation of my apparatus is as follows:-

20 The shale is to be first crushed and is then fed into the retorts 1 through the pipes 31 sufficient to fill them from the grates 5 upward. Heat is then applied, by burning 25 gas through the burners 6 and from the fire on the grates *a*, to and on all sides and ends of the retorts to vaporize the oil in the shale. As said oil is vaporized it passes off as gas through the pipes 10, 11 and 12. The 30 fuel for heat is to be mainly supplied from the by-products of the plant, the gas from uncondensed gas from the retorts, and the fire on the grates *a* from coke, coal or other fuel suitable.

35 As will be obvious the greatest heat will be near the base of the retorts while the heat will diminish gradually upward, and for convenience in describing I will call that portion of the interior of each retort adjacent the lines of pipes 10 as one heat zone 10', that adjacent the pipes 11 as another heat zone 11' and that adjacent the pipes 12 as heat zone 12'. And utilizing this 40 gradual decline in temperature in the shale 45 as the heat rises I have been able to induce differential distillation in the different zones. First the heat is so regulated and utilized that a decline in temperature from the hottest and highest, zone 10' which will 50 be maintained at about 600° centigrade for destructive distillation to that of zone 12' where it will be sufficient to remove all moisture from the shale in zone 12'. This moisture is led off through pipe 30 for condensation 55 if desired. The gas generated in zone 11' will pass off through pipe 28, and by means of valves 27' and 27^a partial refining may be made at this point by controlling the gas from the different pipes 11, while the 60 heavier oil gases will be passed off through pipe 29, and since the volatile products are removed in the zones of heat producing them through the pipes in that particular zone, the use of superheated steam as now practised is unnecessary in my retorts. When

the shale in a retort has been sufficiently treated to remove the oil contents the said grates 5 are dumped by turning their shafts 50 and the treated shale or gangue is allowed to fall into the pit O from which it is to be removed as waste. Partially treated shale may be lowered on to the doors 3 by operating the said grates 5, and the purpose of the double support by the doors 2 and grates 5 is to be able to hold up the weight of the shale by dumping from the grates 5 to the doors 3 and when that much of the contents of the retort is handled or dumped into the said pit O another charge may be lowered and treatment continued. 80 In apparatuses and by processes heretofore used the volatile products from the heat zones are required to pass upward through the granulated shale in the shale tower and the heat must be maintained by superheated steam to properly function by partial pressure, and more or less oil condensation takes place in the upper regions or zones of cooler shale while by the present apparatus the lateral pipes 10 and 11 do away with the superheated steam and loss by such condensation and less heat is required. And since the oil gas is removed from the shale at the actual temperature of its liberation there will be less destructive distillation of the oil gas as 95 the oil will be removed from the shale in its more natural state and will not be subjected to such higher temperatures as will cause chemical decomposition into gaseous and liquid products, carbon and other products 100 which result from extended destructive distillation. A small quantity of steam is introduced through the pipes 8 to produce chemical action on residual hydrocarbons and carbon by which the nitrogen is concentrated for the chemical production of ammonia, carbon-monoxid and hydrogen. The 105 gases are conducted through the pipes 28 and 29 to condensation elements, not shown or claimed as a part of the apparatus, where 110 the baser oils containing the paraffin or asphaltum bases from the pipe 29 may be easily kept separate from the highly volatile oils from the pipe 28.

I thus provide a new and novel process 115 for extracting and partially refined oil from granulated oil bearing shale by the new apparatus shown in the drawings consisting of narrow easily heated retorts having spaced apart perforated pipes thereacross to carry 120 the gas from the different heat zones of the retorts and thereby effect a partial refining of the oil to be recovered by condensing said gas.

Having thus described my invention I desire to secure by Letters Patent and claim:-

1. An apparatus for extracting oil, consisting of a furnace; narrow metal retorts spaced at the sides and ends from the walls of said furnace; means to supply heat in 125

said furnace; a plurality of perforated pipes spaced apart in a vertical plane longitudinally in said retorts and connected in groups by discharge pipes; valve controlled pipes leading from said perforated pipes; and means to pass crushed oil bearing shale through said retorts.

2. An apparatus for extracting oil from shale, consisting of a furnace; means to supply heat in said furnace; narrow retorts spaced apart and from the walls of said furnace; a plurality of perforated spaced apart pipes horizontally and longitudinally disposed in a vertical plane in said retorts; discharge pipes to connect said perforated pipes in groups, and means to pass crushed shale intermittently through said retorts.

3. An apparatus for extracting oil from shale, consisting of a furnace; means to supply heat in said furnace; narrow retorts spaced apart and from the walls of said furnace; a plurality of perforated spaced apart pipes horizontally and longitudinally disposed in a vertical plane in said retorts; discharge pipes to connect said perforated pipes

in groups, and means to pass crushed shale intermittently through said retorts, said means consisting of pipes entering said retorts at the top, and grates and doors in the bottom of said retorts.

4. An apparatus for extracting and refining oil from oil bearing shale, consisting of a furnace; means to supply heat in said furnace; two narrow retorts spaced apart over said heat supply in said furnace and from the walls of said furnace; a plurality of perforated pipes spaced apart and horizontally and longitudinally disposed in a vertical plane in said retorts; discharge pipes connecting said perforated pipes in groups; valves to control the discharge from some of said perforated pipes; feed pipes leading into the top of said retorts; and grates to support and handle said shale while in said retorts and discharge it from the bottom of the retorts.

In testimony whereof I have affixed my signature.

EMIL T. ERICKSON.
